UNITED STATES PATENT OFFICE.

WILLIAM O. BRYANT, OF LOS ANGELES, CALIFORNIA, ASSIGNOR TO UNDERWOOD TYPEWRITER COMPANY, OF NEW YORK, N. Y., A CORPORATION OF DELAWARE.

TYPEWRITING MACHINE.

Application filed October 27, 1921. Serial No. 510,772.

To all whom it may concern:

Be it known that I, WILLIAM O. BRYANT, a citizen of the United States, residing in Los Angeles, in the county of Los Angeles and State of California, have invented certain new and useful Improvements in Typewriting Machines, of which the following is a specification.

This invention relates to typewriting machines, and more particularly to means for rapidly and accurately bringing predetermined portions of inserted work-sheets or elements to the printing line.

The main object of the invention is to provide simple and effective work-positioning and advancing means simple in construction, economical to manufacture, readily assembled and taken apart, easily attached to machines of standard manufacture, and capable of effecting, within a wide range, line-space movements of different extents.

In carrying out the invention, provision may be made of improved platen-rotating means of the type sometimes known as platen-sweep mechanism. Such means may comprise a bracket on which the other parts are supported, so that, when the bracket, with the other parts attached, is secured to the platen-frame and a driving connection effected between the adjacent end of the platen-axle and a rotatable member forming part of the platen-rotating means, actuation of the platen by means of the improved platen-rotating means may be effected.

The rotatable member connected with the platen-axle may consist of a sleeve to receive the end of the platen-axle, a pinion separated from the sleeve by a bearing portion and a finger-wheel outside of said pinion, and may be rotated by means of a gear meshing with said pinion and rotatably supported above the platen-axle by means of a member extending outwardly from the platen-frame parallel to said axle. The connection between said last-mentioned member and the rotatable member may be effected by a plate or member mounted on the gear-carrying member and having an opening in which the bearing portion of the rotatable member is journaled. The gear may be actuated by a handle mounted to turn above the same axis and having a pawl to cooperate with the gear. Suitable stop-

ping means may be provided to limit the forward movement of the handle.

In order to relieve the platen-rotating attachment from the strain exerted thereon during the operation of the handle and also at the time when the latter is checked by the stopping means, the outer end of the gear-supporting element may be supported at its outer end by a member or bar fixed on the carriage and having an opening to receive the gear-carrying member. The opening referred to may be in the form of a slot to permit case-shift movements of the platen. The slotted member may also be provided with a pawl-lifter, so that, when the operating handle is returned to its normal position, as, for example, by a spring, the pawl will be lifted out of engagement with the gear, so that the platen-rotating means, when not in use, will not interfere with the turning of the platen by other means.

A feature of the invention is the provision of means for quickly locating ledger-sheets for writing. At each insertion of a ledger-sheet, a single item or only a few items are entered, and the sheet must be inserted again and again at different times, each time being located in a different writing position in the machine. In accordance with this feature, provision may also be made of an aligning table above the platen, so that, when the usual feed-rolls are cast off, a work-sheet may be passed over the rear paper table and around to the front of the platen, where it may be aligned and exactly positioned by the aligning table. The handle of the platen-rotating means may then be pulled forwardly and the work-sheet or element advanced until the desired writing-line portion thereof is advanced to the writing line indicated by the upper aligning edges of the usual wing-scales. Typing on the ledger-sheet may then be effected. The platen-rotating means may be arranged to advance the platen through distances which are equal to whole numbers of line-spaces, only.

It will be seen that the aligning table and the platen-sweep mechanism form, in combination, a two-step collating device; that is, a device for locating a ledger-sheet by a two-step operation in various mechanically pre-

determined positions at successive insertions, to cause the lines typed at such insertions of the sheet to be equally spaced and parallel to one another. The aligning table effects the first step of the collating operation by gaging the sheet to locate it in a definite uniform position at each insertion, with reference to the printing point, and with its leading edge parallel to the line of writing. The platen-sweep mechanism then effects the second step of the collating operation (a) by advancing the platen to the necessary extent, and (b) locating the sheet in exact position to begin typing thereon; so that fine adjustment of the sheet by the aid of the eye is avoided. In other words, the original gaging of the sheet now has a postponed efficacy, so that the sheet is caused to be advanced from its gaged position exactly to one of the desired typing positions. The platen has a ratchet-wheel, and a spring-detent acts thereon to secure exact positioning of the platen at the end of this second collating step.

25 Other features and advantages will hereinafter appear.

In the accompanying drawings,

Figure 1 is a side elevation, partly in section, showing a work-sheet inserted between the platen and the cast-off feed-rolls and positioned by an aligning table above the platen.

Figure 2 is a diagrammatic side elevation, showing the feed-rolls in effective position against the platen and the work-sheet advanced by a forward movement of the handle of the platen-rotating means.

Figure 3 is a plan view, showing the invention applied to the right-hand end of the platen-frame.

Figure 4 is a vertical section, viewed from the front of the mechanism shown in Figure 3.

A platen 11 is supported by means of an axle 12 journaled in the ends 13 of a platen-frame 14. The platen-frame 14 is mounted in a carriage 15 comprising a transverse bar 16, against which the rear paper-guiding portion of the platen-frame rests when the platen is in lower-case position. Fixed on the left-hand end of the platen-axle 12 is a ratchet-wheel 17, which may be actuated by the usual line-spacing mechanism, including a pawl 18, the platen being held in any position to which it has been turned by means of a detent member 19, having a rotatable roll 20 at its end to engage in the notches between the teeth of the ratchet-wheel 17.

60 In some kinds of work, it is desirable to rotate the platen at a single operation through a much greater angle than is possible by means of the usual line-spacing mechanism. To this end, a novel form of platen-rotating means of the type sometimes

known as platen-sweep mechanism is provided at the right-hand end of the platen-frame. Secured to the vertical flange 21 of the usual cover-plate 22 on the right-hand end of the platen-frame by means of suitable means, such as bolts 23, is a bracket 24 having at its upper end a sleeve 25, in which is secured, by means of a screw 26, the inner end of a pin 27 parallel to the platen-axle 12. Near its outer end the pin 27 is provided with a holding collar 28 and a bearing collar 29 outside of the holding collar 28. Mounted on the pin 27 is a spacing sleeve 30 having a collar 31, so spaced from the end of the sleeve as to permit a gear 32 to be received between the collar 31 of the sleeve 30 and the holding collar 28 of the pin 27 when the parts are assembled. A handle 33 is loosely mounted on the bearing collar 29 and held in position thereon by a sleeve 34 secured to the pin 27 by any suitable means, such as a pin 35. The sleeve 34 is provided with a flange 36 at its inner end integral therewith and with a removable flange 37 at its outer end so as to receive a coil spring 38, one end of which engages the front edge of handle 33 and the other end of which is fixedly connected with the sleeve 34. The spring 38 tends to swing the handle to the rear, and the movement of the handle in this direction is limited by suitable means to be described hereinafter.

The gear 32 meshes with a pinion 39 which is secured by any suitable means, such as a pin 40, on the reduced end 41 of a rotatable member 42 comprising a bearing portion 43 and a sleeve 44 in which the outer end of the platen-axle is secured by means of a screw 45. A finger-wheel 46 may be secured on the reduced end portion 41 outside of the pinion 39 by any suitable means, such as a pin 47. To insure proper operative connection between the gear 32 and the pinion 39, provision is made of a member or bracket 48 mounted on the sleeve 30 and provided with an opening in which the bearing portion 43 of the rotatable member 42 is journaled.

It will be evident that the platen-rotating mechanism just described may readily be applied to the right-hand end of the platen-frame shown. The gear 32 may be placed on the outer end of the sleeve 30 and the pin 27 passed through said sleeve, so that the holding collar 28 will engage the outer end of the sleeve and hold the gear 32 in position against the collar 31, the space between the holding collar and the collar 31 being sufficient to permit movement of the gear independently of the sleeve. The sleeve 30 may be introduced into the upper end of the member 48, into the lower end of which the rotatable member 42 has been inserted so that the bearing portion 43 fits therein, the pinion 39 then being secured on the re-

duced end 41. The sleeve 44 may then be secured to the platen-axle 12 by means of the screw 45, and the inner end of the pin 27 to which the sleeve 30 is fixedly secured 5 may be inserted in the sleeve 25 and secured by the screw 26. The handle 33 and other parts may then be assembled on the outer end of the pin 27 and the finger-wheel 46 may be secured on the reduced end 41 of the 10 rotatable member 42. Obviously, the manner in which these parts are assembled may be varied. The platen-axle 12 is journaled in collars 13^a projecting from the ends 13 of the platen-frame 14, and provision is made 15 of a spacing sleeve 13^b on axle 12 to prevent longitudinal movement of the axle relative to the platen-frame. The detent member 19 and ratchet-wheel 17 cause the platen to come to rest in definite line-space positions, 20 regardless of the means by which the platen is advanced.

Provision may be made for relieving the platen-frame and the platen-rotating attachment from the strain to which they are 25 subjected when the platen-rotating handle 33 is swung forwardly. To this end, the carriage 15 is provided with a usual finger-guard 49, which extends to the right from the front rail 50 of the carriage, and is provided at the rear with brackets 51 carrying a transverse bar 52, at the ends of which are vertical brackets 53.

The downturned end 54 of a bar 55 is 30 connected with a vertical flange 56 of the finger-guard 49 by any suitable means, such as screws 57, and at its rear end the bar 55 is supported on a bolt or bar 59 extending between the brackets 53. The bar 55 is provided with an open slot 60 to receive the bolt 59, and it will be evident that, upon 35 releasing the screws 57, the bar 55 may readily be removed from the bolt 59. The bar 55 is provided with a slot 61 in proper position to receive the outer end of the pin 27, which normally rests in the lower end 40 of the slot. The slotted construction of the bar 55 enables case-shift movement of the platen-frame by means of a shift-frame 62, mounted to swing about the axis of a rod 63 and provided at its forward end with a rod 64, on which rests a roll 65 rotatably 45 mounted on the lower part of the platen-frame 14. Preferably, the slot is closed, as herein disclosed, so that no displacement of the pin 27 to the front or rear or out of 50 the slot may be effected when the frame is in raised position.

A bracket 66 is secured to the bar 55 at 55 the rear of the slot 61 and adjacent the periphery of the gear 32, by means of screw 67. Preferably, the bracket 66 is of sheet-metal, shaped to form a stop 68 for the handle 33 and a finger or pawl-lifter 69 which, when handle 33 is moved to the rear by the spring 38, engages a pawl 70 and

swings it about its pivot 71 to withdraw it from the gear 32 against the action of a leaf-spring 72 secured to the handle 33 by means of a screw 73.

Preferably, in practice, the usual feed-rolls 74 are cast off and a work-sheet 75 is inserted at the rear and positioned at the front of the platen by means of an aligning table or plate 76 having a flange 77 at its upper edge. The feed-rolls 74 are then restored to effective position and the handle 33 drawn forward, the work-sheet 75 being advanced, as indicated in Figure 2, until the desired portion of the work-sheet is brought to the writing line immediately above the aligning edges of wing-scales 79 carried by a type-bar segment 80. The sheets, after alignment on said table 76, should not be advanced beyond the last writing line by handle 33. A stop 84, formed as an extension of member 48, may, therefore, be provided, and the handle in its forward movement will be checked by engagement of a pin 85 thereon with the stop 84 to prevent turning of the sheets out of the machine at 90 the locating operation. Typing may then be effected by means of types 81 on type-bars 82, line-spacing being effected, if desired, by means of the usual line-spacing mechanism at the left end of the platen-frame. Upon release of handle 33, it will be swung to the rear by spring 38 and the pawl 70 moved to ineffective position. The handle 33 may thereafter be used for running the sheet 75 out of the machine after 95 the typing has been completed.

In using the invention, the ledger-sheets are inserted one after another in the machine, and each one is collated by the two-step collating means, comprising the aligning table, the platen-sweep mechanism, and the ratchet-wheel and detent. With the feed-rolls thrown off, the first collating step is effected by inserting a sheet around the platen from the rear and gaging it in a definite exact and uniform position with reference to the printing point or line, by means of the leading-edge gage on the aligning table. The feed-rolls are then restored, and the second collating step is performed by 105 operating the handle 33 to advance the sheet to typing position. The platen-ratchet 17 and the detent 19 acting thereon locate the sheet in exact typing position at the end of the platen-sweep operation. By thus imparting a collating sweep to the platen, the gaged condition of the sheet, both with respect to its alignment and its line-space position as originally determined by the leading-edge gage of the paper-table, is automatically preserved and taken advantage of to cause the new line of writing to be exactly a pre-measured line-space below the last line typed on the sheet at the next previous insertion thereof into the machine. 110

Variations may be resorted to within the scope of the invention, and portions of the improvements may be used without others.

Having thus described my invention, I

5 claim:

1. In a typewriting machine, in combination, a platen, a platen-axle, a platen-frame in which said axle is journaled, a carriage in which said platen-frame is mounted, case-shift mechanism for shifting said platen-frame, a pinion on one end of said platen-axle to rotate the same, a gear-supporting member extending outwardly from the platen-frame parallel to said axle, a gear 10 on said member to mesh with said pinion, means for actuating said gear, and a guide fastened on said carriage and having a slot to receive the outer end of said gear-supporting member so as to guide it during 15 case-shift movements.

2. In a typewriting machine, in combination, a platen, a platen-axle, a platen-frame in which said axle is journaled, a carriage in which said platen-frame is mounted, case-shift mechanism for shifting said platen-frame, a pinion on one end of said platen-axle to rotate the same, a gear-supporting member extending outwardly from the platen-frame parallel to said axle, a gear 20 on said member to mesh with said pinion, an operating arm loosely mounted on said member, a pawl on said arm to actuate said gear, and a guide fastened on said carriage and having a slot to receive the outer 25 end of said gear-supporting member so as to guide it during case-shift movements.

3. In a typewriting machine, in combination, a platen, a platen-axle, a platen-frame in which said axle is journaled, a carriage 30 in which said platen-frame is mounted, case-shift mechanism for shifting said platen-frame, a pinion on one end of said platen-axle to rotate the same, a gear-supporting member extending outwardly from the platen-frame parallel to said axle, a gear 35 on said member to mesh with said pinion, an operating arm loosely mounted on said gear-supporting member, a pawl on said arm to actuate said gear, a guide member fastened 40 on said carriage and having a slot to receive the outer end of said gear-supporting member so as to guide it during case-shift movement, and a pawl-lifter mounted on 45 said guide member to render the pawl 50 effective when said operating arm is in normal position.

4. In a typewriting machine, in combination, a platen, a platen-axle, a platen-frame in which said axle is journaled, a carriage 55 in which said frame is mounted, case-shift mechanism for shifting said platen-frame, a platen-rotating device comprising a gear

and an operating handle mounted on an axis parallel to the platen-axle, and means attached to said carriage to guide said platen-rotating device during case-shift movements.

5. In a typewriting machine, in combination, a platen, a carriage having a finger-guard, with a vertical flange, extending from the right end of the platen-frame, platen-rotating means comprising a pivot above the platen-axle and parallel thereto, and an operating handle pivoted thereon, and means to relieve the platen-rotating means from strain comprising a bar secured to the vertical flange of the finger-guard and supported at its other end on the rear of said carriage.

6. In a typewriting machine, in combination, a platen, a carriage having a finger-guard, with a vertical flange, extending from the right end of the platen-frame, platen-rotating means comprising a pivot above the platen-axle and parallel thereto, and an operating handle pivoted thereon, and means to relieve the platen-rotating means from strain comprising a bar secured to the vertical flange of the finger-guard and supported, on the rear of said carriage, by a rod extending through an open slot therein.

7. In a typewriting machine, in combination, a platen, a platen-frame, a carriage in which said platen-frame is shiftably mounted, platen-rotating means on the platen-frame and shiftable therewith, and means mounted on the carriage, independently of the platen-frame, to support said platen-rotating means against forward and rearward pressure.

8. A platen-rotating attachment to be secured to one end of a platen-frame of a typewriter, comprising a bracket on which the other parts of the attachment are supported, said bracket comprising a sleeve having its axis parallel to that of the platen, a gear support having one end secured in said sleeve, a gear rotatably mounted on said gear support, a rotatable member having a portion to receive the adjacent end of the platen-axle and a pinion to mesh with said gear, a connecting bracket mounted on said gear support and in which said rotatable member is journaled, a handle loosely mounted on said gear support, a pawl on said handle to actuate said gear, a stop on said connecting bracket, and a projection on said handle to engage said stop and thereby check the forward movement of said handle.
